UNITED STATES PATENT OFFICE

2,436,850

AIR BRAKE SLACK ADJUSTER

Edward Lee Bowen, McComb City, Miss.

Application February 20, 1946, Serial No. 648,995

3 Claims. (Cl. 188—198)

1

This invention relates to an automatic slack adjuster for railroad car air brakes.

The principal object of this invention is to provide a slack adjuster of the character described which automatically adjusts brake travel to the limits set by Federal law, namely, between 7" and 9". The way this is done today is to adjust the brakes by hand. In consequence, there are periods between adjusting operations during which the brake travel dangerously approaches the maximum limit set by Federal law and at times actually exceeds it. The present construction is designed to adjust the travel automatically so that as soon as the maximum limit is approached an adjustment is immediately and automatically made. The advantages of such construction are obvious.

Another object of the present invention is the provision of an automatic slack adjuster as described which may be used in connection with standard railroad equipment and which is of simple construction and fool-proof in installation and operation.

A preferred embodiment of this invention is shown in the accompanying drawing in which—

Fig. 1 is a plan view of the slack adjuster herein claimed showing how it is connected to the brake rods and hand brake;

Fig. 2 is a side view thereof;

Fig. 3 is an enlarged fragmentary top view of the main lever of the proposed construction;

Fig. 4 is a section on the line 4—4 of Fig. 3;

Fig. 5 is an edge view of said main lever on the line 5—5 of Fig. 3;

Fig. 6 is a section on the line 6—6 of Fig. 4; and

Fig. 7 is a view of the main lever similar to that of Fig. 3 after it has moved beyond the limits set by Federal law.

Referring now particularly to Fig. 1 a cylinder 10 is shown in which a piston 11 is mounted movably in response to the flow of compressed air through the pipe 12 from the conventional source of compressed air (not shown). This cylinder is connected to the car frame in the usual way by means of bracket 13. The piston rod 15 is connected to one end of the main or master lever 16. Also connected to the piston rod 15 is a chain 17 connected to the hand brake rod 18.

At the other end of the master lever 16 a brake rod 20 is connected leading to one of the trucks of the car. Intermediate said brake rod connection and said piston rod connection is a middle rod 22 which is connected to the master lever 16 by means of a ratchet construction herein-after described and which is connected at its other

2

end to lever 23. Lever 23 is pivoted at 24 to the frame of the car or to a bracket 25 affixed to the frame of the car and at its opposite end it is connected to a brake rod 26 which leads to the other truck of the car. Thus far, with the sole exception of the ratchet construction, the mechanism herein described is conventional.

Reference to Figs. 4, 5 and 7 will show that the master lever 16 is comprised of two arms 10 which, for the most part, are spaced from each other. These two arms do not move with respect to one another and for all practical purposes they may be considered to constitute a single unit, to wit, the master lever 16. The middle rod 22 is connected by means of a pivoted screw member 30 to a ratchet bar 31. It will be seen particularly in Figs. 4 and 5 that this ratchet bar passes between the two arms constituting the master lever 16. The ratchet bar is slotted longitudinally 15 at 32 to accommodate a rivet or pin 33. This rivet affixes a bracket 34 to the master lever 16 as shown in Fig. 4. Slidably mounted on said bracket by means of screw member 36 is a pawl 37. A tension member 38 on said screw member 25 36 tends to force the pawl against the teeth of the ratchet bar 31 to engage the same. A cam 39 on said pawl 37 is positioned to engage the bracket 34 to disengage said pawl from the ratchet bar 31. This action takes place against the tension of the spring or tension member 38. It is a manual operation.

This ratchet construction, together with the two arms which constitute the master lever 16, comprise part of the present invention and they are not found in standard equipment. Nonetheless, so far the apparatus operates in precisely the same manner as does standard apparatus.

The compressed air forces the piston and piston rod 11 and 15, respectively, outwardly and causes corresponding movement of that end of the master lever 16 to which the piston rod 15 is attached. Movement in the same direction of the middle rod 22 is effected. Movement in the opposite direction of the brake rod 20 is similarly effected since this brake rod is connected to the master lever 16 at the end opposite that at which the piston rod 15 is connected. The movement of the middle rod 22 causes corresponding movement of the lever 23 and the brake rod 26. Thus far there is no relative movement between the pawl 37 and the ratchet bar 31.

Reference to Figs. 5 and 7 will show that a secondary or limiting lever 50 is pivoted at one end to that end of the master lever 16 to which the brake rod 20 is connected. Pivotal movement

between the secondary lever 50 and the master lever 16 is thereby provided. The free end of the secondary lever 50 is connected by means of a chain 51 to a bracket 52 on the cylinder 10. This chain limits the movement of the secondary lever 50 to the extent provided by law. It will be noted that secondary lever 50 is provided with a right angle projection or flange 55 through which a rod 56 passes. Said rod is pivotally connected at 57 to the master lever 16. At its free end it is provided with a nut 58 and intermediate said nut and the flange member 55 is a tension member 59. This tension member abuts the nut 58 and the flange 55 and tends to urge the two levers 16 and 50 into registration with each other. When the master lever moves outwardly beyond the maximum limit provided by law as shown in Fig. 7, the chain 51 will prevent corresponding movement of the secondary lever 50 and the master lever 16 will move out of registration with the secondary lever 50 against the action of the tension member 59.

It will be seen in Fig. 4 that an arm 60 is connected at one end to secondary lever 50 and at the other end to a clutch member 61. This clutch member 61 is mounted on the screw member 30 which is connected at one end to the middle rod 22 and at the other end to the ratchet bar 31. This clutch member is constructed in such manner that it will permit free movement of said rod 30 toward the right as seen in Fig. 4 but will clutch said rod 30 when said rod moves to the left.

It will be recalled that a chain 51 limits the movement of the secondary lever 50 toward the right as said lever is shown in all of the figures. When the brake shoes to which the brake rods 20 and 26 are connected become worn, there will be an excessive movement of the piston or thrust rod 15 toward the right. This will in turn cause the master lever 16 to move toward the right a correspondingly excessive distance. Since the master lever 16 is connected by means of the pawl 37 to the ratchet bar 31 and hence to the screw member 30 and the middle rod 22, such excessive movement of the master lever 16 toward the right will effect a corresponding movement of said ratchet bar, screw member and middle rod. To the extent that such latter movement is excessive there will be a slippage of the clutch member 61 with respect to the screw member 30. In consequence, there will be a relative movement between the master lever 16 and the secondary lever 50 as shown in Fig. 7. As has already been indicated, the limit of the movement of secondary lever 50 is determined by the length of the chain 51.

When the brakes are released the several parts of the mechanism described in the foregoing paragraph will return to their original position. Insofar as the two levers 16 and 50 are concerned, the tension member 59 will cause these two levers to move into registration with each other from the position shown in Fig. 7 to the position shown in Figs. 3 and 4. As these two levers move into registration with each other the clutch 61 grips the screw member 30 and moves said member to the right with respect to the master lever 16. As a result there is relative movement between the ratchet bar 31 and the pawl 37 and a consequent shortening of the effective length of the middle rod 22.

The slot 70 in the ratchet bar 31 permits of this relative movement between the ratchet bar and the master lever 16. A slot 71 formed at that end of middle rod 22 which engages the lever 23 is provided as a safeguard. Should the lever hang, the

rod will slide back over it thus preventing undesired shortening of piston travel.

It will be understood from the foregoing that what has been described is simply a preferred embodiment of the invention and that variations thereof are possible without departing from the basic principles of the invention. The key to the present invention lies in the use of a ratchet mechanism which is controlled by a member having a predetermined limit of movement.

I claim:

1. In an automatic slack adjuster for air brakes, a compressed air cylinder, a compressed air actuated piston in said cylinder, a floating lever connected to said piston, a brake rod connected to said floating lever, a connecting rod connected to said floating lever, a dead lever connected to said connecting rod and a second brake rod connected to said dead lever, the connection between the connecting rod and the floating lever being by means of a ratchet mechanism controlled by a clutch which operates on said connecting rod, whereby relative movement between said connecting rod and said floating lever may be effected to shorten the operative length of said connecting rod when the piston travel exceeds a predetermined range, said clutch being itself controlled by a third lever which is pivoted at one end to the dead lever and connected at the other end to the compressed air cylinder by means of a chain of predetermined length, said third lever being connected intermediate its ends to the clutch by means of a rod of predetermined length, said lever being also connected intermediate its ends to the dead lever by means of a spring which urges said dead lever and said third lever into registration with each other.

2. In an automatic slack adjuster for air brakes, a compressed air actuated piston, a floating lever connected to said piston, a brake rod connected to said floating lever, a connecting rod connected to said floating lever, a dead lever connected to said connecting rod and a second brake rod connected to said dead lever, the connection between the connecting rod and the floating lever being by means of a ratchet mechanism controlled by a clutch which operates on said connecting rod, said clutch being connected to a tether of predetermined length to cause relative movement between said clutch and said connecting rod to the extent that said connecting rod moves beyond a predetermined range, and a compression spring acting in conjunction with said clutch for causing relative movement of said connecting rod and said floating lever through said ratchet mechanism to shorten the operative length of said connecting rod.

3. In an automatic slack adjuster for air brakes, a compressed air actuated piston, a floating lever connected at one end to said piston, a brake rod connected to said floating lever at the opposite end thereof, a connecting rod connected at one end by means of a ratchet construction to said floating lever intermediate the two ends thereof, a dead lever connected to the opposite end of said connecting rod, and a second brake rod also connected to said dead lever, a control lever, a compression spring which normally holds said control lever in registration with said floating lever, a chain of predetermined length limiting the movement of said control lever, and a clutch connected to said control lever and operating on said connecting rod, whereby travel of said floating lever beyond a predetermined limit will carry said floating lever

out of registration with the control lever against the action of the compression spring and on the return movement of said floating lever, the clutch will grip the connecting rod and the compression spring will cause relative movement between said connecting rod and said floating lever through the ratchet construction, bringing the control and floating levers back into registration with each other, and shortening the effective length of said connecting rod.
